UNITED STATES PATENT OFFICE

156,070

DESIGN FOR A HUNTING KNIFE

Oakley Brooks, Columbus, Ohio

Application July 17, 1947, Serial No. 140,339

Term of patent 14 years

(Cl. D22—3)

To all whom it may concern:

Be it known that I, Oakley Brooks, a citizen of the United States of America, residing at Columbus, in the county of Franklin and State of Ohio, have invented a new, original, and ornamental Design for a Hunting Knife, of which the following is a specification, reference being had to the accompanying drawing, forming a part thereof.

Fig. 1 is a perspective view of a hunting knife, showing my new design;

Fig. 2 is a top plan view thereof;

Fig. 3 is an end elevational view looking toward the blade end of the knife.

I claim:

The ornamental design for a hunting knife, substantially as shown and described.

OAKLEY BROOKS.
